Primary Examiner — Barbara Fox(74) *Attorney, Agent, or Firm* — Tutunjian & Bitetto, P.C.(57) **CLAIM**

The ornamental design for a tablet, as shown and described.

DESCRIPTION

FIG. 1 is a front view of the tablet with a stand, according to my new design;

FIG. 2 is front perspective view thereof;

FIG. 3 is a back view thereof;

FIG. 4 is a rear perspective view thereof;

FIG. 5 is a right side view thereof; and,

FIG. 6 is a right side view thereof with the stand extended. The broken lines shown in the drawings represent portions of the tablet that form no part of the claimed design.
